UNITED STATES PATENT OFFICE

137,264

DESIGN FOR A FLASHLIGHT OR LIKE ARTICLE

Joshua Gordon Lippincott, Scarsdale, N. Y., assignor to Guth, Stern & Co., Inc., a corporation
of New York

Application November 29, 1943, Serial No. 111,810

Term of patent 14 years

To all whom it may concern:

Be it known that Joshua Gordon Lippincott, a citizen of the United States and resident of Scarsdale, in the county of Westchester and State of New York, has invented a new, original, and ornamental Design for Flashlight or Like Article, of which the following is a specification, reference being had to the accompanying drawing forming part thereof, in which,

Fig. 1 is a side elevational view of a flashlight or like article showing my new design, and

Figs. 2 and 3 are front and rear elevational views thereof.

I claim:

The ornamental design for a flashlight or like article, as shown.

JOSHUA GORDON LIPPINCOTT.
